[57] **CLAIM**

The ornamental design for an accessory kit to be attached to an athletic shoe, as shown and described.

DESCRIPTION

FIG. 1 is an exploded left side elevational view of an accessory kit to be attached to an athletic shoe showing my new design;

FIG. 2 is a rear view of a portion of the kit thereof;

FIG. 3 is a front view of the kit thereof;

FIG. 4 is a top view of the kit thereof;

FIG. 5 is a bottom view of the kit thereof;

FIG. 6 is a front view of a portion of the kit in its closed position, the rear view being a mirror image thereof;

FIG. 7 is an exploded left side elevational view thereof;

FIG. 8 is a top view thereof; and,

FIG. 9 is a bottom view thereof.

The broken line showing of a left athletic shoe in all figures is for illustrative purposes only and forms no part of the claimed design.
